MEANS FOR REPAIRING FRACTURED
CASTINGS

Lawrence B. Scott, Houston, Tex.

Application November 28, 1940, Serial No. 367,540

10 Claims. (Cl. 189—36)

This invention relates to new and useful improvements in methods and means for repairing fractured castings and structures of a similar nature.

I have disclosed in my Patent No. 2,195,741, issued April 2, 1940, and in my pending application, Serial No. 259,594, filed March 3, 1939, various methods and means of repairing cracked or fractured castings or structures of a similar nature. It has been found, that it is desirable to provide means for expanding the locks which are used as said locks are forced into position within the casting.

It is, therefore, one object of this invention to provide an improved method and means for repairing damaged castings, or articles of a similar nature, wherein the locking member is expanded as it is forced into position in the casting.

Another object of the invention is to provide a locking member of such configuration as to materially increase the efficiency of said member under various conditions.

Still another object of the invention is to provide an improved method and means of repairing damaged castings, or articles of a similar nature, whereby corners, edges, and angular projections on said castings may be repaired.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a plan view of a locking member, constructed in accordance with the invention, and showing the locking member in position in a casting.

Figure 2 is a vertical, longitudinal, sectional view taken on the line 2—2 of Figure 1.

Figure 3 is a plan view of another form of the locking member.

Figure 4 is a vertical, transverse, sectional view taken on the line 4—4 of Figure 3.

Figure 5 is an enlarged, vertical, cross-sectional view showing one of the locking members in position within a casting.

Figure 6 is an isometric view of a further modification of the locking member showing the member in position upon a corner or an edge of a casting.

Figure 7 is a longitudinal, sectional view of the locking member shown in Figure 6, and

Figure 8 is a transverse, sectional view of the

locking member shown in Figure 6 of the drawing.

In the drawing, the numeral 10 designates a fractured member. This method of repairing damaged structures is particularly applicable to metallic castings or similar articles of a relatively frangible nature, however, the invention may be utilized to repair many different types of structures or to strengthen said structures at points of stress.

In carrying out the teachings of this invention, a plurality of elongate recesses 11 are formed in the face of the fractured member in such a position as to extend transversely of the fracture 12 which appears in Figures 1 and 2 of the drawing. It is pointed out, that the recesses may be formed in any suitable or desirable position with respect to the member 10 or the fracture 12. The recesses have been shown in the drawing as extending transversely of the fracture only for reasons of illustration. The recesses may be placed longitudinally with respect to the fracture or at an angle thereto. Each individual member is subject to stresses of varying magnitudes and directions. For this reason, each individual member must be reinforced in a manner best adapted to that particular member, and therefore the position occupied by the recesses 11 is determined by the configuration of the fractured member 10 and the stresses said member is subjected to.

The recesses 11 are of such a shape as to receive locking members 13. The members 13, as shown in Figures 1 and 2, are elongate and are provided with laterally extending, semi-circular lugs 14. The lugs 14 are formed in pairs along the length of the member so as to have one lug of a pair directly opposite the other. Any suitable number of lugs may be utilized since the members may be of any desirable length, and any suitable spacing of said lugs may be employed. It is not necessary for the lugs to be formed in transverse pairs, however, such a configuration has been found to be particularly efficient.

A plurality of vertical openings 15 are formed along the longitudinal axis of each of the locking members 13. The openings 15 are so spaced along the members 13 so as to have one opening between each of the pairs of lugs 14. Such a spacing is not essential to the invention but is advantageous. The openings 15 are tapered downwardly so as to have their lower cross-sectional area greater than their upper cross-sectional area, and a tapered pin 16 fits into each of said openings.

In installing the locking members, the recesses 11 are formed in the surface of the member 10. The pins 16 are inserted into the openings 15 of the locking members 13, and said locking members are positioned within the recesses 11. It is pointed out that the pins 16, as they are inserted into the openings 15, extend a short distance below the under side of the locking members. With the members 13 in this position, a suitable punch (not shown) is utilized to drive the locking members downwardly into the recesses 11. This operation forces the tapered pins 16 upwardly within the openings 15 and spread said openings, thereby causing the locking members to spread into snug engagement with the walls of the recesses 11. In this manner the locking members are securely positioned in the face of the casting so as to protect said casting from subsequent damage due to the stresses placed upon the latter. The locking members are preferably formed of a material capable of withstanding high tensile stresses so that said members may absorb any stress which may be placed upon the fractured member. Obviously, the lugs 14 lock the members 13 to the member 10 so that there can be no slippage of the members 13 within the member 10. Although such a structure is not shown in the drawing, it is to be noted that the recesses 11 may be formed deep enough in the fractured member so as to receive more than one of the locking members 13. In such an instance, each individual locking member would be hammered into position with a punch before the next succeeding member is placed in position in the recess. The locking members are stacked, one upon the other, within the recess in this manner until the recess is full of said members.

A modification, or second form, of the invention is shown in Figures 3, 4 and 5 of the drawing. This modification is very similar to the first form of the invention, described hereinbefore, and is placed or installed in the fractured member in the same manner. The locking member utilized in the second form of the invention is an elongate bar 20 having semi-circular recesses 21 formed along each side thereof. The recess 22 in which the bar 20 is positioned will be of such a configuration as to conform to the shape of said bar. An elongate groove 23 is formed longitudinally of the bar 20 and extends throughout the length of said bar. The groove 23 is substantially V-shaped in cross-section, having the V inverted so as to have its apex extending upwardly. An elongate V-shaped wedge 24 fits within the groove 23 so as to extend a short distance below the under side of the bar 20. The wedge 24 functions in a manner similar to the pins 16 of the first form of the invention in that it causes the bar 20 to spread into snug engagement with the walls of the recess 22 when the bar is forced into position within said recess. Obviously, the groove 23 and the wedge 24 could be replaced by a plurality of tapered openings and tapered pins (not shown), similar to the openings 15 and the pins 16 shown in the first form of the invention; or the pins 15 and 16 could be replaced by a groove and wedge similar to the groove 23 and the wedge 24. Both structures serve to spread or expand the locking member into snug engagement with the walls of the recess in which the member is mounted, and could be utilized with any suitable or desirable shape of locking member.

A further modification of the invention is shown in Figures 6, 7 and 8 of the drawing. This

third form of the invention is particularly adaptable in instances wherein it is desired to mount a locking member upon a corner of a casting or fractured member. In this form of the invention a locking member 30 is employed, said member being provided with depending lugs 31. The lugs 31 may be of any suitable cross-sectional size and shape, and may be spaced from one another in any desirable manner. The top side of the member 30 is formed so as to conform with the shape of the article being repaired when the locking member is in position within said article. In the particular installation shown in the drawing (Figures 4, 5 and 6) the locking member is formed with an inverted V-shaped top surface. A tapered opening 32 extends axially of each of the lugs 31, and a tapered pin 33 is disposed within each of said openings. The pins 33 function in the same manner as the pins 16 and the wedge 24 in that they expand the locking member 30 into snug engagement with the article being repaired.

This third form of the invention is installed in the same way as the first and second forms of the invention. A suitable recess 34 is cut in the face of the damaged article, and the locking member 30 is placed in said recess. The pins 33 have previously been inserted in the openings 32, and, as the locking member is hammered or forced into position, the pins expand said member into snug engagement with the walls of the recess 34, whereby the member is securely mounted and locked in position within the recess.

All of the three forms of the invention which have been shown in the drawing, and which have been described in detail hereinabove, have several attributes in common with one another. The locking members are provided with lugs or recesses which lock said members to the casting or article being repaired. The locking members are expanded into snug engagement with their respective recesses by means of wedge members, said wedge members being elongate wedges or tapered pins. With the locking members in such a position, the fracture or crack being repaired is closed and held closed; or, in any event, is prevented from becoming larger. The locking members absorb the tensile and compressive stresses to which the casting is subjected at the damaged location, and prevent said stresses from inflicting further damage upon the casting. As pointed out hereinbefore, the locking members may be installed at a point in a casting where excessive stresses are known to occur. In the latter instance, the locks are preferably installed before the casting is broken or fractured, and serve to strengthen the casting and prevent such breaks or fractures.

What I claim and desire to secure by Letters Patent is:

1. The combination with a casting of a reinforcing member including, an elongate integral element having its longitudinal axis disposed parallel to the surface of the casting and within a recess formed in said casting, and a wedge member having its base portion bearing against the bottom of the recess adapted to expand the element into snug engagement with the walls of said recess.

2. In combination with a casting, a reinforcing member adapted to be inserted at a point of stress including, an elongate integral element positioned within a recess formed in the casting with its longitudinal axis parallel to the surface of said casting, and a plurality of wedge members

having their base portions bearing against the bottom of the recess adapted to expand the element into snug engagement with the walls of said recess.

3. The combination with a casting of a reinforcing member including, an elongate integral element disposed within a recess formed in the casting with its longitudinal axis parallel to the surface of the casting, the recess having depressions formed in the walls thereof, the element having projections complementary to and engaging within the depressions of said recess, and a wedge member having its base portion bearing against the bottom of the recess adapted to expand the projections into snug engagement with the depressions of said recess.

4. The combination with a casting of a reinforcing member including, an elongate integral element disposed within a recess formed in the casting with its longitudinal axis parallel to the surface of the casting, the element having a plurality of openings formed therein, and a plurality of tapered members engaging within the openings with their base portions bearing against the bottom of the recess and adapted to expand said element into snug engagement with the walls of said recess.

5. The combination with a casting of a reinforcing member including, an elongate integral element disposed within a recess formed in the casting with its longitudinal axis parallel to the surface of the casting, the element having a groove formed in its lower surface, and a wedge member engaging within the groove with its base portion bearing against the bottom of the recess and adapted to expand said element into snug engagement with the walls of said recess.

6. The combination with a casting of a reinforcing member including, an elongate integral element disposed within a recess formed in the casting with its longitudinal axis parallel to the surface of the casting, the element having a plurality of openings formed in its lower surface, and a tapered pin engaging within each opening with its base portion bearing against the bottom of the recess and adapted to expand said element into tight engagement with the walls of said recess as the element is forced thereto.

7. The combination with a casting of a reinforcing member including, an elongate integral element disposed within a recess formed in the casting with its longitudinal axis parallel to the surface of the casting, the recess having depressions formed in the walls thereof, the element

5 having projections complementary to and engaging within the depressions of said recess, said element having a plurality of openings formed therein, and tapered pins engaging within the openings with their base portions bearing against the bottom of the recess and adapted to expand the element and its projections into snug engagement with the walls of said recess and the depressions thereof.

10 8. The combination with a casting of a reinforcing member including, an elongate integral element disposed within a recess formed in the casting with its longitudinal axis parallel to the surface of the casting, the recess having depressions formed in the walls thereof, the element having projections complementary to and engaging within the depressions of said recess, said element having a V-shaped groove formed in its lower surface, and a wedge member engaging within the groove with its base portion bearing against the bottom of the recess and adapted to expand the element and its projections into snug engagement with the walls of said recess and the depressions thereof.

20 9. The combination with a casting of a reinforcing member including, an elongate integral element disposed within a recess formed in the casting with its longitudinal axis parallel to the surface of the casting, the recess having depressions formed in the walls thereof, the element having laterally-extending lugs complementary to and engaging within the depressions of said recess, and a wedge member having its base portion bearing against the bottom of the recess adapted to expand said element and its lugs into snug engagement with the walls of said recess and the depressions thereof.

25 10. The combination with a casting of a reinforcing member including, an elongate integral element disposed within a recess formed in the casting with its longitudinal axis parallel to the surface of the casting, the recess having depressions formed in the walls thereof, the element having laterally-extending lugs complementary to and engaging within the depressions of said recess, said element having a plurality of openings formed in the lower surface thereof, and a wedge member engaging within each opening with its base portion bearing against the bottom of the recess and adapted to expand said element and its lugs into snug engagement with the walls of said recess and the depressions thereof.
